(21) Appl. No.: **29/249,378**

(57) **CLAIM**

(22) Filed: **Oct. 4, 2006**

The ornamental design for a infra red receiver for PC, as shown.

(30) **Foreign Application Priority Data**

Apr. 19, 2006 (EM) 000514781

DESCRIPTION

(51) **LOC (8) Cl.** **14-02**

FIG. 1 is a perspective view showing my design;

(52) **U.S. Cl.** **D14/358**

FIG. 2 is a front elevational view thereof;

(58) **Field of Classification Search** D13/184;

FIG. 3 is a rear elevational view thereof;

D14/356-358; 361/600, 601, 622, 641, 679,

FIG. 4 is a right side elevational view thereof;

361/683, 686, 814; 439/248

FIG. 5 is a left side elevational view thereof;

See application file for complete search history.

FIG. 6 is a top plan view thereof; and,

(56) **References Cited**

FIG. 7 is a bottom plan view thereof.
